UNITED STATES PATENT OFFICE

130,460

DESIGN FOR A COLLAR OR SIMILAR
ARTICLE

David Rosen, New York, N. Y.

Application October 21, 1941, Serial No. 103,849

Term of patent 3½ years

To all whom it may concern:

Be it known that I, David Rosen, a citizen of the United States of America, residing in New York city, county of New York, and State of New York, have invented a new, original, and ornamental Design for a Collar or Similar Article, of which the following is a specification, reference being had to the accompanying drawing, forming part thereof, wherein,

The figure of the drawing is a plan view of a collar showing my new design.

I claim:

The ornamental design for a collar or similar article, substantially as shown.

DAVID ROSEN.
